Inventor

UNITED STATES PATENT OFFICE.

BERT E. MINKLER, OF CARTHAGE, MISSOURI.

FOOTWEAR-CLEANER.

1,117,883.

Specification of Letters Patent. Patented Nov. 17, 1914.

Application filed March 29, 1913. Serial No. 757,586.

To all whom it may concern:

Be it known that I, BERT E. MINKLER, a citizen of the United States, residing at Carthage, in the county of Jasper and State 5 of Missouri, have invented certain new and useful Improvements in Footwear-Cleaners, of which the following is a specification, reference being had therein to the accompanying drawing.

10 It is an object of this invention to provide a brush-carrying frame for devices of this character that can be stamped or fabricated from a single piece of sheet metal, thereby materially reducing the cost of manufacturing such devices. Further, the device is so arranged that the brush for cleaning the bottom of an article of footwear, which requires comparatively frequent cleaning, may easily be removed for that purpose and as 15 readily replaced.

When read in connection with the description herein, the details of construction and arrangement of parts contemplated by the invention will be apparent from the accompanying drawing, forming part hereof, wherein an embodiment of the invention is disclosed, for purposes of illustration.

While the embodiment disclosed by the drawing, now is considered a preferable one, 30 it is to be understood that it is not the intention to be limited necessarily to the exact form shown, as it is obvious that alterations can be made within the limits prescribed by the claims, without departing from the nature and spirit of the invention.

Like reference-characters refer to corresponding parts in the views of the drawing, of which—

Figure 1 is an end view; Fig. 2 is a top 40 view; Fig. 3 is a top view of the frame; Fig. 4 is a side view and Fig. 5 is a view of the bottom-cleaning brush.

Having more particular reference to the drawing, 6, 7, and 8 designate brushes or the like for respectively cleaning the bottom, sides, and top of articles of footwear. The brushes are supported by a frame 9 of sheet metal, which is attached to any suitable base by screws or the like 10. The material of 45 the frame is bent upwardly at oppositely-disposed end portions to form side flanges 11, and to these flanges are riveted or otherwise secured, near the junction of the flanges with the remaining plane portion of the 50 frame, spring-arms 12, the arms on each side extending upwardly and toward the arms

on the other side. To the ends of the arms on each side is attached a side brush 7. In order to afford auxiliary supports for brushes 7 and to take some of the weight 60 and strain imposed upon the brushes, the material of the frame is cut beneath the brushes and portions of the material bent upwardly to form uprights 13 on the ends of which the brushes rest. 65

In order to hold the central bottom-cleaning brush 6 removably in place, the material of the frame between the uprights 13 is cut and portions of the material turned to form flanges 14. The flanges 14 are spaced apart 70 a sufficient distance to permit the base of the brush 6 to be placed therebetween, the flanges clamping the brush and holding it against lateral movement. Each of the flanges has an inturned lug 15 arranged to 75 seat in a slot 16 in the brush-base when the brush is between the flanges, whereby longitudinal movement of the brush is prevented. The material of one of the side flanges 11 is cut and a portion of the material turned 80 outwardly to form a horizontally-disposed bottom-scraper 17 near one end of that flange. The material of one of the flanges 11, preferably that on which the scraper 17 is formed, is cut near one end and a portion 85 of the material bent outwardly and upwardly to form a support 18 to which the top or toe cleaning brush 8 is secured.

It will be noted that the various parts for holding the brushes in place, except the 90 spring-arms, are formed integrally on and from a single piece of sheet metal in a simple manner, so that the cost of making the supporting-frame is comparatively small. When the wearer of an article of footwear 95 desires to clean it, he moves the foot carrying the article back and forth between the side brushes and over the lower brush, whereby the sides and bottom of the footwear are cleaned, the spring-arms during 100 this operation pressing the side brushes against the footwear and permitting the brushes to give laterally. Mud and the like may be removed from the bottom of footwear by moving it over the scraper, and at 105 the same time the top of footwear will come into contact with the brush 8 and be cleaned. When it is desired to remove the bottom-cleaning brush, it may be lifted from the frame. Usually, the bristles of the bottom 110 and side brushes will give sufficiently to permit upward movement of the bottom brush

on removal, or the side brushes may be moved laterally to permit this operation.

Having thus described my invention, what I claim as new, and desire to secure by Letters Patent, is—

1. In a footwear-cleaning device, the combination of a frame, flanges on the frame having inturned lugs, a bottom-cleaning brush between said flanges and having slots 10 in which said lugs are seated, spring-arms on the frame, on said arms oppositely-disposed side-cleaning brushes, and on said frame uprights constituting auxiliary supports for said side-cleaning brushes.

2. A footwear-cleaning device comprising a frame, upwardly-extending spring arms secured near each end of said frame, oppositely disposed brushes on said arms, and uprights on the frame and below each brush and constituting an auxiliary support there- 15 20

In testimony whereof I affix my signature in presence of two witnesses.

BERT E. MINKLER.
